UNITED STATES PATENT OFFICE.

WILLIAM SCHOOF, JR., OF MILWAUKEE, WISCONSIN.

CARBURETER.

1,135,729.

Specification of Letters Patent. Patented Apr. 13, 1915.

Application filed January 28, 1909. Serial No. 474,753.

To all whom it may concern:

Be it known that I, WILLIAM SCHOOF, Jr., a citizen of the United States, residing at Milwaukee, county of Milwaukee, and State 5 of Wisconsin, have invented new and useful Improvements in Carbureters, of which the following is a specification.

My invention relates to improvements in carbureters for internal combustion engines. 10 The object of my invention is to provide a mixing valve in which the quality of the gas or combustible mixture will not be materially affected by variations in the speed of the engine or in the quantity of the mixture 15 received by the engine cylinder and in which the supply to the engine will be controlled both as to quantity and quality by adjusting a single valve, and no valve adjustments will be required to control the supply of liquid 20 hydro-carbon.

In the following description, reference is had to the accompanying drawings, in which—

Figure 1 is a vertical sectional view of a 25 carbureter involving my invention. Fig. 2 is a sectional view drawn on line $x-x$ of Fig. 1. Fig. 3 is an operative, diagrammatic illustration of one of the air inlet and one of the vapor outlet ports, the latter being 30 versed in position, with dotted lines indicating the relative effect of the valve upon the capacity of the two ports as it moves from open to closing position; the air inlet port being also provided with a dotted line 35 indicating the relative capacity of the vapor outlet port when fully open. Fig. 4 is a detail view of the valve and its seat. Fig. 5 is a detail view of the valve actuating stem. Fig. 6 is a detail view of the crank P, oscillatory stem P' and spiral segment Q.

Like parts are identified by the same reference characters throughout the several views.

The valve casing A is provided with an oil 45 inlet duct B and an air inlet duct C, the mixed gases being delivered to the engine through a duct D. The oil delivered through the duct B is derived from a chamber E in which the oil is maintained at a 50 constant level, preferably by means of a float e, operatively arranged with reference to a valve actuating lever F, which operates to open a spring actuated valve G controlling the delivery of oil to the valve G from a 55 source of supply through a filtering cham-

ber G' and a duct g. A screen or filter H is preferably employed in the filtering chamber G'. A spring g' normally holds the valve G to its seat, from which the valve is lifted when the float e bears upon the free end of the lever F, the admission of the hydro-carbon to the chamber E being thus controlled by the float so that the level of the liquid in the chamber remains substantially constant. 60

The stem I of the valve G is slidingly mounted in a nut I', which may be provided with a vent J, whereby the pressure in chamber E, which also has a vent J', remains constant. 65

A cup-shaped valve seat K receives oil from the duct B through its base, this duct B extending longitudinally in a standard L and receiving oil from the chamber E through a series of comparatively small apertures b in such standard. The standard passes through a central aperture in the float e and the walls e' of said aperture preferably diverge upwardly, so that when the carbureter is used for portable engines, the float 70 can adjust itself to the level of the liquid in the chamber E without binding upon the standard. 75

The valve seat K is provided with a series of triangular ports K', the side walls of 80 which converge downwardly to an apex at or near the base of this valve seat. These ports communicate between the valve cavity and an annular cavity M in the casing, which cavity in turn communicates with the vapor 85 outlet D.

A reciprocating valve N in the form of an inverted cup extends downwardly in the air inlet C and telescopes within the valve seat K with its lower margin in normal open position in close proximity to the upper margins of the vapor outlet ports K'. This valve is provided with air inlet ports O, of substantially the same shape as the ports K' and having the same dimensions when measured in the direction of valve movement, but with the side walls of each port diverging upwardly at an angle which is slightly less than the angle of divergence of such walls in the port K', the difference in total capacity 90 thus produced being such that the vapor outlets K' have a capacity when the valve is fully open sufficiently in excess of that of the air inlets O, to produce a suction at the oil inlet and to secure the delivery of the 95 100 105 110 115 120

requisite amount of hydro-carbon, which, when vaporized, will nearly compensate for the difference in capacity in the ports K' and O.

5 It will be observed that with the valve in the position illustrated in Fig. 1, any movement toward closing position will cause the margin of the valve N to move across the triangular ports K' from their large toward 10 their small end, and as these ports are triangular in form, the area remaining open in any given adjustment will always be equal to the square of the ratio of the distance to be traveled by the valve from full 15 open position to the total distance from full open to closed position. It will also be observed that the upper margin of the valve seat K will simultaneously have a relative inovement across the ports O, commencing 20 however at the apexes of the triangular openings and moving toward the larger end of base, the closing movement for any given distance traveled reducing the area of these ports in the square of the ratio which the 25 distance of valve travel bears to the total distance to be traveled from full open to closed position, thus also conforming to the above stated theoretical rule.

With the described form of the ports and 30 the arrangement of the valve as above set forth, if the valve is moved one quarter of the distance from full open to closed position, it will close but one-sixteenth of the air inlet, leaving these ports at 15/16 of their full 35 capacity. The vapor outlet ports, however, will have only 9/16 of their full capacity, 7/16 of their total area having been cut off by the same valve movement. If the valve is moved half way from full open to closed 40 position, 1/4 of the total area of the air inlet ports and 3/4 of the vapor outlet ports will have been cut off. When the valve is closed three-quarters of the total distance, 9/16 of the area of the air inlet and 15/16 of 45 the vapor outlet area will have been cut off.

I have found that with ports of such form, they will be closed in inverse proportions, as above described, the quality of the mixture will remain substantially un- 50 changed in all positions of valve adjustment and the vapor delivered through the outlet ports K' will burn uniformly with a blue flame, thus demonstrating that a theoretically perfect mixture is secured. The suction at 55 the oil inlet is regulated, not only by the withdrawal of vapor through the vapor outlet ports, but by the proportionate admission of air at the air inlet ports, and I find that only by varying the relative capacity 60 of these ports in the proportions stated, can a perfect mixture, burning with a blue flame under all adjustments, be secured.

The valve N may be conveniently actuated 65 by means of a crank P, the swinging motion of which is transmitted to the valve through

a vertical stem P', spiral segment Q and valve stem N', the latter being provided with angular rack teeth Q' engaged by the spiral segment Q.

The valve seat K is preferably secured to 70 the upper wall of the chamber E by means of a head piece R carried by the upper end of the standard L, the standard being passed through an aperture in the base of the valve seat K, and the head piece being shouldered 75 to fit the annular margin of said aperture. The standard passes downwardly through the chamber E and is provided within this chamber with a nut R' adapted to clamp the valve seat K and the upper wall of the 80 chamber E between it and the head piece R. Packing nuts S are also preferably employed where the standard passes through the lower walls of the chambers E and G'. Another structural feature designed to 85 provide for wear is that of providing the cylindrical portion of the valve with a slit T, the valve being bored eccentric, and composed of material having sufficient resiliency to produce an expanding pressure upon the 90 walls of the seat K. The seat K may also be provided with a projection t entering the slit T, whereby the valve N is kept from rotating.

The specific form of construction shown 95 and described herein is not essential to my invention, it being immaterial what form of structure or arrangement of the valve, valve seat, or other parts are employed to regulate the areas of the air inlet and vapor 100 outlet ports as herein described. It will be understood, therefore, that the terms and phrases employed in this description and the appended claims are employed as terms of description and not of limitation, it not being my intention to exclude from the scope 105 of my invention any mechanical equivalent for the construction shown and described.

Having thus described my invention, what I claim as new, and desire to secure by Letters Patent, is—

1. A carbureter comprising the combination of a walled passage, provided with triangular air admission and mixture outlet ports and an intermediate inlet for liquid 115 hydro-carbon, of means for closing said ports simultaneously from the bases of the triangular mixture outlet ports toward their apexes, and from the apexes of the triangular air ports toward their bases, said port 120 closing means traveling an equal distance across the respective ports.

2. A carbureter comprising the combination of a walled passage, provided with triangular air admission and mixture outlet 125 ports and an intermediate inlet for liquid hydro-carbon, of means for closing said ports simultaneously from the bases of the triangular mixture outlet ports toward their apexes, and from the apexes of the triangu- 130

lar air ports toward their bases, said port closing means traveling an equal distance across the respective ports, said air ports, when fully open, being of sufficiently less capacity than the mixture outlet ports, to secure the described suction at the outlet.

In testimony whereof I affix my signature in the presence of two witnesses.
